UNITED STATES PATENT OFFICE.

EVAN P. BONE, OF CINCINNATI, OHIO.

HEADLAMP.

1,389,291.

Specification of Letters Patent. Patented Aug. 30, 1921.

Application filed January 8, 1920. Serial No. 350,073.

To all whom it may concern:

Be it known that I, EVAN P. BONE, a citizen of the United States, and a resident of Cincinnati, in the county of Hamilton 5 and State of Ohio, have invented new and useful Improvements in Headlamps, of which the following is a full, clear, and exact description, reference being had to the accompanying drawings, forming a part of this specification.

My invention relates to headlamps, and has particular reference to such headlamps as are designed for use with motor vehicles.

The principal object of the present invention is to provide in a headlamp means whereby the projected beam may be defined within limits whereby glare in the eyes of opposing drivers or pedestrians is prevented.

20 A further object of the present invention, and one incidental to the principal object above mentioned, is to obtain, in connection with the elimination of objectionable glare, improved road illumination.

25 In order that the roadway may be satisfactorily and economically illuminated, it is desirable that substantially even illumination be made at both long and short ranges. To effect this the rays intended for illumination at long ranges must have greater density than those intended for illumination at shorter ranges. In headlamps as at present designed and generally in use, the beam of light from the lamp fringes away 30 so gradually from the area of greatest concentration of the rays, that if substantially adequate illumination at long ranges be obtained, the rays projected into the eyes of opposing drivers or pedestrians are of sufficient density to produce undesirable and dangerous glare, even when the eyes are not in the portion of the beam of greatest intensity. This condition results by reason 35 of the fact that the angle between the light rays reaching the road at long ranges, which of course, should be the rays of greatest concentration, and those reaching the eyes of opposing drivers or pedestrians is comparatively small.

40 In attaining the objects of the present invention, I employ in a headlamp, an image forming lens having such dimensions that there is a conjugate focal point inside the lamp for each point in the field of illumination, viz: the roadway and objects upon 45 and to the side thereof. These conjugate

focal points within the lamp cover an imaginary surface which approximates and for all practical purposes may be spoken of as a plane. The illumination, therefore, of 50 any point along the roadway and in the general field of illumination, is dependent upon the quantity of light emitting from its conjugate focal point in said plane. In connection with the image forming lens I 55 also employ suitable means, as for instance the peculiarly constructed reflector, and the screen hereinafter described, for predetermining with economy and precision the quantity of light emitted from each of these 60 conjugate focal points within the lamp. By these several means the distribution of rays along the roadway is effected as desired and, as will be seen, the illumination of the roadway at long ranges may be intensified while 65 at the same time the beam is sharply cut off so that glare in the eyes of approaching persons is prevented.

With the foregoing and further objects in view, as will more fully hereinafter appear, 70 the present invention consists of details of construction herein fully described.

In the particular embodiment of my invention selected for illustration—

Figure 1 is a central longitudinal section 75 of a headlamp constructed in accordance with this invention.

Fig. 2 is a diagrammatic view, illustrating the principle of operation of said lamp.

Fig. 3 is a diagrammatic view illustrating 80 the principles of satisfactory road illumination.

Fig. 4 is a detail of the screen from the rear.

Fig. 5 is a sectional view of a modified 85 form of screen construction.

The numeral 1 indicates the main casing or body of the lamp constructed in accordance with this invention. Mounted in said body is an ellipsoidal reflector 2, having its 90 foci at 3 and 3^a, the front portion of the reflector, however, assumes a more gradual curve as shown and extends into the front part of the lamp. Arranged to fit on the casing 1 is a front portion 4 within which 95 an aplanatic lens 5 is mounted. The reflector 2, front 4 and lens 5 are all tightly fitted together so as to be dust proof in accordance with usual electric headlamp practice. The lens is so disposed with reference to 100 the casing that the principal rearward focus thereof is approximately in the cross sec-

tional plane 9—10 within the body of the lamp, in which plane also the focal point 3 of the ellipsoidal reflector 2 is located. The plane 9—10 may be considered the focal 5 plane of the lens. The lens may be of any aplanatic construction, by which I mean generally devoid of spherical aberration. The use of the aplanatic lens permits the 10 employment of a lens of extraordinarily wide aperture, in comparison with its focal length, such aperture being essential in order to accommodate the pencil of rays diverging from the focus at a wide angle, to obviate the necessity of extreme length in 15 the body of the lamp. The lens as used is also an exceptionally wide angle lens but the absence of aberration is not so essential except at points near the center of the field. Mounted in the lamp, in the plane 9—10, 20 is also a screen 6. The screen 6 as illustrated in Fig. 4, is of generally rectangular form and has an upper projection 7 at one side of the middle thereof for the purpose hereinafter set forth. The support 8 of the 25 screen 6 is bent so that the vertical section will be removed some distance from the focal plane 9—10. As illustrated in Fig. 5, the screen 6 may be arranged for vertical adjustment by means of an electro-magnet 30 11, operated from a convenient place in the vehicle. The forward portion of the support of the screen 6 is secured to the body 4 of the lamp by means of a spring 12, which draws it downwardly against the threaded 35 pin 13. The support of the screen 6 is pivoted at 14, and as will be seen, when the electro-magnet 11 is energized the screen will be raised against the tension of the 40 spring 12. The lamp is provided with a socket for an electric bulb 15, the filament of which is located at the focal point 3^a of the reflector 2. The reflector incloses the bulb so as to 45 collect a major portion of the rays radiating therefrom.

The principle of operation of the device is illustrated in the several figures of the drawings by means of typical rays indicated by broken lines. Rays from the filament of 50 the bulb 15 striking the ellipsoidal portion of the reflector 2 are concentrated in the plane 9—10, around the point 3, the cross-sectional area of the concentration being proportional to the size of the filament, in 55 accordance with optical laws. Other rays reflected from the forward portion of the reflector pass the focal plane 9—10 at various points, the density thereof decreasing gradually away from the area of concentration at 3. The forward portion of the reflector extends well into the front half of the lamp, causing rays to enter the lens from exceptionally wide side angles to make 60 possible the illumination of a correspondingly wide field. The lens 5 is, as above

stated, arranged relative to the plane 9—10, so that said lens throws an optical image of whatever may be located in said plane into the field of illumination and the mapping out of the light distribution over the 70 plane forms a plan, in miniature, of the light to be distributed over the roadway in effecting a desired illumination.

In Fig. 2 for the purpose of illustrating the principle of the present invention, I have indicated the field of illumination as a theoretical plane 16 parallel with the plane 9—10. Rays passing the area of concentration 3, in the plane 9—10, being of maximum density, the projected image thereof 80 will be more brightly illuminated, and this portion of the optical image is indicated at 17. All of the rays passing the plane 9—10 at any other one point as for instance 18, in Fig. 2, will be projected to its conjugate 85 focal point in the optical image, for instance the point 19 on the plane 16. The rays at the point 18, however, being of less density, as above set forth, than the rays at the point 3 in the area of concentration, said portion 90 of the image will be of correspondingly less brilliance, as indicated in the image on the plane 16; and as aforesaid, as the density gradually decreases to the edges from the point 3, the brilliance of the image gradually 95 decreases radially from the area of greatest brilliance 17. The screen is located in the focal plane 9—10 of the lens 5, and the image of said screen will therefore be projected with sharp definition into the field 100 of illumination as indicated at 20 on the plane 16, the downwardly projecting portion 21 to the left of the center of illumination 17 as viewed from the lamp, being the optical 105 image of the upper projection 7 of the screen 6.

The screen is opaque and therefore blocks out rays from the portion of the focal plane covered by it; hence the portions 20—21 of the field of illumination are in comparative 110 darkness. It is, of course, only by placing the screen 6 in the focal plane of the lens 5 that sharpness of definition of the area of darkness 20—21 can be obtained, but it may be given any location in said plane consonant 115 with a desired result. Since however, the portion of the beam of greatest intensity must strike the roadway at farthest range in order to secure satisfactory and economical road illumination, the screen 6 should, of 120 course, be located in or near the area of concentration around 3 in order that the dark area may be located at the proper angle of elevation above the roadway at practicable operating ranges, this angle being very 125 small. Thus the screen forms a partial border to the concentrated area around 3, so that, the dark area 20—21 in the image appears to partly border the bright area 17. The dark area must, however, only partly border the 130

bright area so as not to cut off the light below 17 which is needed for close range illumination.

- From the foregoing description of the optical principle of the lamp it may be noted that two distinct means,—the reflector and the screen,—are used for controlling the intensity of the light emitting from the various points in the plane 9—10 to the lens. 5 The reflector operates with economy while the screen operates with precision and each is used where its particular feature is most needed. The reflector is economical because it functions without loss of light by 10 interception as the rays pass the plane; and having any fixed available quantity of light radiating from the filament source, the same is collected by the reflector which by the varying angles of its surface directs said 15 light to the various points in the plane with a concentration and distribution best suited for illumination. However, by reason of the appreciable size of the source of light, imperfections in the reflector, and deviations 20 of the source of light from accurate location in the focus of the reflector, the concentration of the rays at any particular point as intended is indefinite, causing a blurring effect. This effect is not necessarily objectionable except at certain critical locations 25 where bright light as emitting from certain points must be prevented from closely adjacent points. At such locations the screen is used and, although losing light by interception, it serves to block out the rays along 30 sharply defined limits with the accuracy required to illuminate the roadway at long range without projecting glaring light into the eyes. 35 Changes may be made from the precise form of headlamp herein shown and described, within the scope of accompanying claims, without departing from the principles of my invention and without sacrificing 40 its objects and advantages. 45 In order to utilize some of the intercepted light the screen 6 may have a reflecting surface, 6^a. In Fig. 5 of the drawings I have 50 illustrated the intercepted ray 29 being reflected as shown by the line 30 to the ellipsoid reflector 2. 55 In Fig. 3 I have illustrated diagrammatically the application of the present lamp to road conditions. In said figure the arc 60 22—23 represents the angle of the projected beam of sufficient intensity for useful illumination, and while this beam is of greatest intensity near the center, except where darkened by the screen, it is at all points within 65 this angle of such brilliancy as to cause objectionable glare. In placing the lamp 24 on the vehicle, the same is so disposed with relation thereto that the bright central portion 17 of the optical image reaches the roadway at 25 and the area of darkness 20, the
- optical image of the screen 6, has its lower edge approximately on the line 26 below the eyes of a person located at 25 on the roadway, the line 27 indicating the elevation at which rays would cause glare in the eyes of 70 said person. The rays of the beam illuminate the roadway from a point 28, but as they decrease in density radially from the central portion 25 of the beam, the density of the rays reaching the roadway decreases 75 from the central portion toward the vehicle. As the shorter distances require less flux density than the greater ranges to obtain equivalent illumination, this decreasing of the density from the center serves to give the 80 roadway a nearer uniform illumination. The distribution of the light along the roadway in this manner accords with the standards of efficiency and economy in headlighting for the reason that the illumination at 85 close ranges does not have to be unduly bright in order to obtain sufficient brightness for long range. The angular width of the close range illumination is of necessity greater than that of long ranges. The distribution of light as illustrated on plane surface 16, shows how the concentrated area 17 is only a small percentage of the total area of the field and the large saving in light by 90 having the large outer zones as 19 of less 95 brilliance than the center 17. The substantially sharp definition between the concentrated portion of the beam 17 and the dark area 20, permits the change from maximum concentrated light at 25 to the no glaring 100 light at 27, within the necessarily small angle.
- The dark area 21, produced by the projection 7 of the screen 6, is on the left side of the roadway as viewed from behind the lamp 105 and comes in alignment with the position of an approaching vehicle when the two vehicles have turned aside to pass, thus providing an additional factor of safety against glare when the car having these headlamps 110 receives upward tilts from uneven roads or abnormal loading. The screen forming the dark area 20—21 may, however, be designed in various shapes and sizes as is consistent with the general object of preventing glare 115 and providing long range illumination during the greatest number of circumstances on varied road conditions. Inasmuch as the positions of the eyes of opposing drivers are, in general, above and to the left of the surface 120 of the roadway, the darkened area is correspondingly disposed, in general, above and to the left of the central portion of the beam. Whether it is entirely above, entirely to the side, or both, and of whatever size and 125 proportions is a matter of design or specified requirements. It will be understood that the geometrical relations of the size and shape of the dark area 20—21 to the illuminated areas 17, etc., are similar to those of the 130

screen 6—7 to the concentrated light in the plane 9—10 in accordance with well known laws of optics.

The means provided in this invention for projecting a real optical image do not necessarily have to be of a structure permitting the degree of refinement required in devices generally used for projecting images upon a screen to form pictures.

10 By means of the adjusting mechanism illustrated in Fig. 5 the normal angle of elevation of the projected beam may be somewhat higher than would be necessary actually to prevent glare, the area of darkness 15 being lowered by raising the screen 6 through the mechanism illustrated and above described.

Having thus fully described my invention, what I claim as new, and desire to secure by 20 Letters Patent, is:

1. In a headlamp in combination with the casing and a source of light, a projecting lens mounted in said casing, having focal points inside the body of said lamp conjugate with a field of desired illumination, means for concentrating rays from said source of light at a point in the focus of said lens inside the lamp, and means for distributing rays from said source in gradually decreasing density radially from said point of concentration over the focal plane of said lens inside the lamp.

2. In a headlamp in combination with the casing and a source of light, a projecting lens mounted in said casing, having focal points inside the body of said lamp conjugate with a field of desired illumination, an ellipsoid reflector for concentrating rays from said source of light at a point in the focus of said lens inside the lamp, and a reflector for distributing rays from said source in gradually decreasing density radially from said point of concentration over the focal plane of said lens inside the lamp.

45 3. In a headlamp in combination with the casing and a source of light, a projecting lens mounted in said casing, having focal points inside the body of said lamp conjugate with a field of desired illumination, 50 means for concentrating rays from said source of light at a point in the focus of said lens inside the lamp, means for distributing rays from said source in gradually decreasing density radially from said 55 point of concentration over the focal plane of said lens inside the lamp, and means for intercepting a portion of said rays.

4. In a headlamp in combination with the casing and a source of light, a projecting lens mounted in said casing, having focal points inside the body of said lamp conjugate with a field of desired illumination, an ellipsoid reflector for concentrating rays from said source of light at a point in the 65 focus of said lens inside the lamp, a reflector

for distributing rays from said source in gradually decreasing density radially from said point of concentration over the focal plane of said lens inside the lamp, and means for intercepting a portion of said rays.

5. In a headlamp in combination with the casing and a source of light, a projecting lens mounted in said casing, having focal points inside the body of said lamp conjugate with a field of desired illumination, means for concentrating rays from said source of light at a point in the focus of said lens inside the lamp, means located in the focal plane of said lens for intercepting a portion of said rays, and means for moving said intercepting means in said plane.

6. In a headlamp in combination with the casing and a source of light, a projecting lens mounted in said casing, having focal points inside the body of said lamp conjugate with a field of desired illumination, means for concentrating rays from said source of light at a point in the focus of said lens inside the lamp, means for distributing rays from said source in gradually decreasing density radially from said point of concentration over the focal plane of said lens inside the lamp, means for intercepting a portion of said rays, and means for moving said intercepting means in said plane.

7. In a headlamp in combination with the casing and a source of light, a projecting lens mounted in said casing, having focal points inside the body of said lamp conjugate with a field of desired illumination, an ellipsoid reflector for concentrating rays from said source of light at a point in the focus of said lens inside the lamp, means for intercepting a portion of said rays, and means for moving said intercepting means in said plane.

8. In a headlamp in combination with the casing and a source of light, a projecting lens mounted in said casing, having focal points inside the body of said lamp conjugate with a field of desired illumination, an ellipsoid reflector for concentrating rays from said source of light at a point in the focus of said lens inside the lamp, a reflector for distributing rays from said source in gradually decreasing density radially from said point of concentration over the focal plane of said lens inside the lamp, means for intercepting a portion of said rays, and means for moving said intercepting means in said plane.

9. In a headlamp in combination with the casing and a source of light, an aplanatic projecting lens mounted in said casing, having focal points inside the body of said lamp conjugate with a field of desired illumination, means for concentrating rays from

said source of light at a point in the focus of said lens inside the lamp, means located in the focal plane of said lens for intercepting a portion of said rays, and means 5 for moving said intercepting means in said plane.

10. A headlamp comprising an ellipsoidal reflector, a source of light at one focus of the reflector, an aplanatic lens in the lamp 10 having a principal focus at the other focus of the reflector, and light intercepting means mounted within the lamp laterally adjacent said principal focus of the lens.

11. In a headlamp of the character indicated, 15 the combination of an electric incandescent source of light, a lens having its rearward focal plane within the headlamp, and a deeply cupped ellipsoidal reflector to direct a preponderance of the light rays toward said lens, said reflector having one focus at said source of light and the other substantially at said rearward focal plane of the lens, and a screen substantially in said focal plane and encroaching upon the 25 area of intense light concentration at one side thereof.

12. In a headlamp of the character indicated, the combination of an electric incandescent source of light, a lens having its 30 rearward focal plane within the headlamp, and a reflector surrounding the source of light hemispherically and extended thence forwardly to direct a preponderance of the light rays toward said lens; said reflector 35 being formed with its closed end ellipsoidal and having one focus at the source of light and the other at the rearward focal plane of the lens, and having said adjacent reflecting surfaces of lesser curvature, where- 40 by the distribution of light rays in said rearward focal plane comprises a comparatively small area of intense concentration surrounded by a large area of less concentration; and a screen so placed as to partly 45 encroach upon said area of intense concentration.

13. In a light concentrating and projecting device, the combination of a source of light; means for concentrating the rays of said light within the device, means for projecting the rays of said light when concentrated, said latter means having a focal plane within the device, the concentrating means being shaped so as to produce the greatest light concentration substantially in the focal plane of said projecting means, and light intercepting means located substantially in said focal plane and partly covering said area of intense light concentration and at one side thereof. 50

14. In a headlamp, the combination of a source of light, a lens having a rearward focal plane within the headlamp, a light concentrating reflector adapted to produce its area of greatest light concentration in the rearward focal plane of said lens and a screen substantially in said focal plane and partly encroaching upon said area of greatest light concentration but not surrounding same. 55

15. In a headlamp having a source of light; a reflector having an ellipsoidal surface to produce the greatest light concentration within the lamp; adjacent portions of said reflector having a lesser curvature than 60 said first mentioned ellipsoidal portion, a lens in the front of said lamp whose rearward principal focus is substantially in the same cross-sectional plane as said greatest light concentration and a screen substantially in said plane of the focus and light concentration area so placed as to partly encroach upon said area of greatest light concentration but not surround the same. 70

16. In combination with a headlamp having a source of light, a light concentrating reflector and a lens having its rearward principal focus within the headlamp; a screen substantially in the rearward focal plane of said lens and contiguous to said focus 90 and only partly surrounding said focus. 80

EVAN P. BONE.
